UNITED STATES PATENT OFFICE

119,956

DESIGN FOR A DISPLAY STAND

Daniel J. Gomez, Sacramento, Calif.

Application January 24, 1940, Serial No. 89,675

Term of patent 14 years

To all whom it may concern:

Be it known that I, Daniel J. Gomez, a citizen of the United States, residing at Sacramento, county of Sacramento, State of California, have invented a new, original, and ornamental Design for a Display Stand, of which the following is a specification, reference being had to the accompanying drawing, forming part thereof.

The figure is a perspective view of a display stand showing my new design. The opposite side of the stand is identical in appearance to the side shown.

I claim:

The ornamental design for a display stand, as shown and described.

DANIEL J. GOMEZ.
